METHOD AND APPARATUS FOR TESTING CERTAIN CHARACTERISTICS OF PAPER AND THE LIKE

Frank F. Oehme and Michael L. Swanson, Wisconsin Rapids, Wis., assignors to Consolidated Papers, Inc., Wisconsin Rapids, Wis., a corporation of Wisconsin

Filed Nov. 30, 1966, Ser. No. 598,037
13 Claims. (Cl. 73—150)

ABSTRACT OF THE DISCLOSURE

An improved method and apparatus for testing the piling propensity of paper or the like where a specimen of the paper to be tested is mounted on one of a pair of oppositely disposed anvil members and the two anvil members are moved into face-to-face engagement under pressure and one of the anvil members is then rotated about its longitudinal axis relative to the other anvil member, after which one of the anvil members is suddenly moved axially away from the other anvil member, thereby subjecting the test specimen to both rubbing and pick forces in a predetermined timed sequence.

The present invention relates to a method and apparatus for testing certain characteristics of paper, and it is particularly useful in testing the piling propensity of coated offset papers.

In web offset printing, a web of paper is conducted over an offset roller or cylinder having a blanket thereon which picks up ink from a printing plate and applies it to the paper. Where both sides of the paper are being printed simultaneously, the web of paper may be conducted through a nip formed by two adjacent blanket cylinders, whereas if only one side of the paper is being printed the web may be conducted through a nip formed between an offset blanket cylinder and an impression roller. The considerations to be discussed below apply to each of the foregoing situations, but for purposes of discussion we will consider the application where a paper web is conducted between a pair of offset blanket rollers for printing simultaneously on both sides of the web.

It is well known in the art of printing on a multicolor offset lithographic press that a specially treated printing cylinder is prepared having an image formed thereon, and water or fountain solution is applied to the printing cylinder. In the image or printing areas of the cylinder the water is repelled, whereas the water remains on the non-image areas of the cylinder. Consequently, when ink is applied to the printing cylinder, the ink remains on the image or printing areas and is repelled by the water in the nonimage areas. Thereafter, when the printing cylinder contacts the offset blanket, it applies ink to the blanket in the image areas while applying water or fountain solution to the nonimage areas.

One of the most serious problems encountered in offset printing is known as "piling" and constitutes the contamination of the offset blanket with partially water soluble material from the coated offset papers being printed. Such a phenomenon usually occurs on one or more units of multicolor offset lithographic presses where partially water soluble coating material from coated offset papers contaminates the offset blanket, there being a gradual building up or "piling" of such material on the blanket during an accumulative process which develops with the number of printing impressions and is dependent upon the wet re-

2

sistance of the paper and various printing press variables.

When two adjacent blanket cylinders press against one another at the nip defined therebetween, the blankets become slightly flattened so as to reduce the radius of each blanket at the contact area thereby causing a slightly lower peripheral speed at such area. The foregoing effect can produce a rubbing or frictional force between the blankets and a web of paper passing through the nip thereby causing contamination of the blankets with coating material from the paper. Similar rubbing or frictional forces between the blankets and the paper web can also be produced where due to the foregoing flattening of the blankets or for other reasons the radii of two adjacent blanket cylinders are not quite equal to one another at the contact area. Another cause of piling occurs when a blanket is not wrapped on its cylinder with sufficient tension so that a wrinkle or the like develops which moves around the periphery of the cylinder producing rubbing between the blanket and the paper web passing thereover. Friction between the blanket and the paper web is also sometimes produced by a lubricating effect caused by any imbalance of the ink and water on the blanket.

In addition to the various causes of piling or contamination of a blanket with coating material from offset coated papers due to rubbing between the blanket and the paper web, another quite different cause of piling relates to the picking action which occurs when the paper web is peeled away from the blanket. When the paper web leaves the nip between two blanket cylinders it will tend to follow one of the blankets, usually the one having the most ink thereon, and the web as it moves along its predetermined path is stripped or peeled away from the blanket causing a picking action which again may tend to cause some of the coating material on the paper to adhere to the blanket.

From the foregoing discussion it will be seen that piling is produced due to rubbing or friction between the paper web and the blankets as the web passes through the nip defined therebetween, and in addition due to a picking action as the web leaves the nip and is peeled away from the blankets. We have found that both rubbing and picking forces are significant causes of piling on the nonimage areas of a blanket, while picking appears to constitute the major cause of piling on the image areas, the reason for the latter being that the lubricating effect of the ink tends to reduce piling caused by rubbing or friction in the image areas.

The piling or transfer of coating material from coated offset papers to a printing blanket is known to cause various serious problems after it has had an opportunity to accumulate on the blanket. For example, piling can decrease blanket life and make the blanket difficult to clean, and it can also affect the operation of the printing plates. The effectiveness of the fountain solution may also be reduced with the result that some ink may be present in the nonimage areas of the printing plate and on the blanket. Moreover, when there is an accumulation of coating material on the image areas of the blanket, the result may be that all of the ink will not be transferred to the paper, thereby producing a piling of ink on the blanket.

The most effective known means for avoiding the foregoing and other problems caused by piling is to control the offset paper during the manufacture thereof so as to reduce its piling propensity, and in order to accomplish this it is necessary to have available a reliable test for determining the piling propensity of coated offset paper. It is known in the art to conduct a wet pick test in order

to determine the piling propensity of paper, and one such test method and apparatus are described in U.S. Patent 3,129,586, which is assigned to the assignee of the present invention. However, a wet pick test is not sufficiently accurate because it does not indicate the piling propensity of paper when subjected to a rubbing action, and thus it is particularly inadequate as an indication of piling in the nonimage areas of a blanket where both rubbing and picking forces are significant causes of piling. It is also known to conduct a wet rub test as an indication of the piling propensity of paper, but such a test is deficient as a true indication of piling propensity both as to the image areas and the nonimage areas of a blanket because it does not take into account piling produced by a picking action.

It should further be understood that some types of coated offset papers will show a high resistance to piling in a pick test, and a low resistance to piling in a rub test, or vice versa, and thus such tests do not provide an accurate indication as to what the piling propensity of the paper will be when subjected to rubbing or frictional forces and picking forces during an actual printing operation. Moreover, it is important to note that merely to conduct separate wet pick tests and wet rub tests on samples of offset papers would still not provide reliable results, since in an actual printing operation the rubbing or frictional forces and the pick forces occur in a certain sequence and time relationship which effects the degree of piling resulting from the combination thereof.

It is therefore a general object of the present invention to provide an improved method for determining the piling propensity of paper by simulating the combined effect of rubbing forces and pick forces in a single test thereby providing an unusually reliable indication of the degree of piling which will occur in an actual printing operation.

Another object of the invention is to provide apparatus for carrying out the foregoing method including a pair of anvil members one of which moves toward and away from the other to produce picking forces therebetween, and one of which is rotatable relative to the other to produce rubbing forces therebetween.

A further object of the invention is to provide apparatus which applies rubbing or frictional forces and pick forces to a test sample in a predetermined timed sequence so as to approximately duplicate the timing of application of such forces to a paper web during an actual printing operation.

The foregoing and other objects and advantages of the invention will be apparent from the following description thereof.

Now, in order to acquaint those skilled in the art with the manner of practicing the method of the present invention and making and using the apparatus thereof, we shall describe, in conjunction with the accompanying drawings, certain preferred embodiments of the invention.

In the drawings:

FIGURE 1 is an elevational view showing test apparatus constructed in accordance with the teachings of the present invention;

FIGURE 2 is a plan view of the lower portion of the apparatus looking approximately in the direction of the arrows 2-2 of FIGURE 1;

FIGURE 3 is an enlarged fragmentary vertical sectional view, partly in elevation, taken substantially along the line 3-3 of FIGURE 1; and

FIGURE 4 is a schematic electrical wiring diagram of the controls for the apparatus of FIGURE 1.

Referring now to the drawings, FIGURE 1 shows an upright post 10 from which there is supported a vertically disposed air cylinder 12. A piston rod 14 extends downwardly from the lower end of the cylinder 12 and carries an upper anvil member 16 thereon. The piston rod 14 is normally in an upper or retracted position as shown in FIGURE 1 and is movable downwardly

during a testing cycle, as will appear more fully later herein. A pedestal 18 is disposed beneath the upper anvil 16, and a baseplate 20 is screwed or otherwise fixedly secured to the top of the pedestal 18, the baseplate 20 including a base member 22 and a pair of upright end walls 24 and 26.

A generally U-shaped integral bearing housing 28 comprises a horizontal upper wall 30, a pair of vertical side walls 32 and 34, and a pair of horizontal mounting flanges 36 and 38 extending outwardly from the side walls and permitting the housing to be fixedly secured to the baseplate 20 by a plurality of cap screws or the like 40. A lower anvil 42 is rotatably carried immediately above the wall 30 of the bearing housing and is driven by an air cylinder 44 and reciprocating rack member 46. The air cylinder 44 has a piston rod 48 which is connected to one end of the rack 46 by an adapter 50, and upon operation of the cylinder 44 to push the rack 46 to the right as viewed in FIGURE 1, the rack acts to rotate the lower anvil 42 in a manner to be described more fully later herein.

The degree of rotation of the lower anvil 42 is controlled by an adjustable stop screw 52 which limits the linear stroke of the rack 46. The stop screw 52 is threaded through the baseplate end wall 26 and is provided with a knurled knob 54 at one end thereof so that by manually rotating the screw its longitudinal position may be adjusted to vary the stroke of the rack member 46, the latter being in alignment with the stop screw for engagement therewith. A knurled nut 56 is threaded on the screw 52 and may be rotated into engagement with a boss 58 fixed to the baseplate wall 26 in order to lock the stop screw in a selected position. In addition, an indicator wheel 60 is fixed to the stop screw 52 for rotation therewith, and a scale 62 is supported from the baseplate 20 by a bracket 64. The indicator wheel 60 and scale 62 serve to indicate the position of the stop screw 52 which in turn controls the degree of rotation of the lower anvil 42, and the scale 62 is preferably marked in degrees or in turns, e.g., from 0 to 2 turns, so as to facilitate positioning of the adjustable stop screw in accordance with the desired rotation of the lower anvil.

As best shown in FIGURE 3, the lower anvil 42 has integral therewith a mounting shaft comprising a first shaft section 64 and a reduced diameter shaft section 66. The shaft section 64 is journaled in an upper bushing 68 which is pressed into an opening in the wall 30 of the housing 28, and the lower shaft section 64 is journaled in a lower bushing 70 which is pressed into an opening in the baseplate 22. A ball thrust bearing 72 is positioned on the shaft section 66 immediately above the baseplate 22, and a spur gear 74 having a plurality of peripheral gear teeth 76 is located on the shaft section 66 above the thrust bearing 72. The spur gear 74 is keyed to the shaft section 66 by a key member 78 so that rotation of the spur gear will cause rotation of the lower anvil 42. A collar 80 is positioned on the lower end of the shaft section 64 beneath the upper bushing 68 and is fixed to the shaft by means of a set screw 82.

It will be understood from the foregoing that any downward force on the anvil 42 will be transmitted by the lower end of the shaft section 64 to the spur gear 74 and then to the ball thrust bearing 72, and in this manner the lower anvil 42 is supported so as to be spaced a short distance above the wall 30 of the bearing housing 28, the anvil thus being free to rotate upon rotation of the spur gear 74. A dial 84 (see FIGURE 2) is mounted on the top of the housing plate 30 beneath the lower anvil 42, and the dial extends around the periphery of the anvil so as to provide an indication of the rotary movement thereof. Thus, the anvil 42 may have a reference mark on the side thereof, and the dial 84 may be graduated in fractions of a turn. Assuming the reference mark on the anvil 42 is initially aligned with a "start" position on the dial 84, the location of the reference mark relative to the dial after

rotation of the anvil 42 will indicate the angle through which the anvil has rotated, thus providing a check as to the setting of the adjustable stop screw 52.

A shaft 86 is mounted in spaced parallel relation to the anvil shaft 64, 66, the shaft 86 being disposed intermediate the anvil shaft and the rack member 46. The upper end of the shaft 86 is journaled in a bushing 88 which is pressed into an opening in the housing plate 30, and the lower end of the shaft 86 is journaled in a bushing 90 which is pressed into an opening in the baseplate 22. The shaft 86 is formed with an integral collar 92, and a spur gear 94 is mounted on the shaft immediately above the collar and is keyed to the shaft for rotation therewith by means of a key member 96. The spur gear 94 has a plurality of peripheral teeth 98 which mesh with a plurality of teeth 100 formed on the rack member 46. A guide bar 102 is fixed to the baseplate 22 by a plurality of screws 104, and the rack member 46 moves in a linear path between the guide bar and the spur gear 94 so as to be held in driving engagement with the latter.

A second spur gear 106 is mounted on the shaft 86 above the first-mentioned spur gear 94 and is keyed to the shaft for rotation therewith by a key member 108. The spur gear 106 is substantially larger in diameter than the spur gear 94 and is provided with a plurality of peripheral teeth 110 which mesh with the teeth 76 formed on the spur gear 74. It will now be understood that when the air cylinder 44 is actuated so as to push the rack member 46 to the right as viewed in FIGURES 1 and 2, until the end of the rack abuts the end of the stop screw 52, the rack 46 will act through the spur gears 98, 106, and 74 to rotate the lower anvil 42 through a predetermined angle of rotation dependent upon the stroke of the rack member as controlled by the adjustable stop screw 52.

The lower anvil 42 has a layer of double-faced adhesive tape 112 applied to the top thereof, and a disc-shaped anvil plate 114 is mounted on the top of the tape. The tape 112 thus serves as an electrical insulator between the lower anvil 42 and the anvil plate 114, and as will be more fully understood hereinafter such an insulator or dielectric is necessary when the apparatus is used for penetration testing. A piece of offset blanket material 116 is attached to the bottom surface of the upper anvil 16 with double-faced pressure sensitive tape or any other suitable adhesive means.

In conducting a test of a sample piece of coated paper, the test sample is preferably attached by double-faced pressure sensitive tape or the like to the blanket 116 at the bottom of the upper anvil 16. The blanket 116 provides a relatively permanent cushion which compensates for surface irregularities of the test sample and small variations in contact between the upper anvil 16 and the lower anvil plate 114. A small piece of black plastic electrician's tape or other suitable material, preferably dark in color, is placed on the upper surface of the rotatable lower anvil plate 114, and a single drop of aqueous solution such as lithographic fountain solution is placed on the electrician's tape directly under the upper anvil 16.

During a test cycle the upper anvil 16 is moved downwardly into engagement with the lower anvil plate 114, thus pressing the test sample between the two anvils, more specifically, between the blanket 116 on the upper anvil 16 and the black tape on the lower anvil plate 114, causing the fountain solution to be spread over the contact area so that any excess moisture is squeezed out. A predetermined time after the upper anvil 16 engages against the lower anvil plate 114, the lower anvil plate is rotated through a predetermined angle, after which the upper anvil is suddenly retracted upwardly at a controlled speed so as to separate the test sample from the black tape on the lower anvil plate. Finally, the lower anvil plate 114 is rotated back to its original position. The piling propensity of the test sample is determined by examination of the black tape so as to measure the amount of coating material which has been transferred thereto from the test

sample, the coating material being more or less white in color and thus being readily visible on the tape.

The foregoing test cycle and the control apparatus for regulating the same will now be described in greater detail in conjunction with FIGURE 4. A function switch 118 has a three-position switch arm 120 movable for cooperation with a selected one of three terminals 122, 124 and 126. The arm 120 is moved to the upper terminal 122 for a penetration test, as will be described later herein; it is moved to the lower terminal 126 for pick tests and combination pick-rub, as will be described hereinbelow; and the center terminal 124 is the off position.

A combination pick-rub test will now be described and it will thus be assumed that the function switch arm 120 is engaged with the terminal 126. In order to initiate a test the operator closes a main power switch 128 and manually presses a start push button 130 to its closed position so as to complete a circuit through lines 132, 134, 136, 138 and 140 to a four-way solenoid valve 142 which is integral with the air cylinder 12. The valve 142 is normally positioned so that the piston rod 14 and upper anvil 16 are in their upper or retracted positions, and completion of the circuit as described above initiates downward movement of the anvil 16.

It will be noted that when the start button 130 is closed it also completes a circuit through lines 132, 134, 136, 138, 144 and 146 to a relay 148a thereby closing a normally open relay contact 148b. In this manner, an alternate holding circuit is completed from the power terminal 150 through lines 132, 134, normally closed contacts 152b and 154b and normally open contact 148b, and lines 144 and 140 to the solenoid valve 142 so that the air cylinder 12 will continue downward movement of the anvil 16 after the start button 130 has been released.

FIGURE 1 shows a pin 164 which is carried by the upper anvil 16 and moves between the arms of a guide bracket 166 which is affixed to a mounting plate 168 by a plurality of screws 170. There is also provided a microswitch 172 which is operable by a pivotally movable actuator rod 174, the latter extending into the path of the pin 164 as the upper anvil 16 descends toward the lower anvil plate 114. Accordingly, before the upper anvil 16 reaches the lower end of its stroke, the pin 164 will engage the rod 174 and close the switch 172. As shown in FIGURE 4, the closing of the switch 172 completes a circuit through lines 132, 134, 136, 176, time delay relay 152a, function switch 118, line 178, switch 172 and line 162 to the solenoid valve 142, while at the same time energization of time delay relay 152a opens normally closed contact 152b in the previously described circuit to the valve 142.

Accordingly, after closing of the microswitch 172, the upper anvil 16 will continue down to the lower end of its stroke and will remain in its down position under the force of the air cylinder 12 for a time interval controlled by the time delay relay 152a. In the particular embodiment which is being described by way of example only, the time delay relay 152a can be set for any desired time interval between 0 and 60 seconds. When the selected time expires, the time delay relay 152a will open causing the solenoid valve 142 to admit air to the opposite end of the cylinder 12 thereby returning the upper anvil 16 to its original retracted position. However, in the test being described, other operations occur before the retraction of the upper anvil, as will be described hereinbelow.

It will be noted from FIGURE 4 that upon the closing of the microswitch 172, normally open contact 152c is closed thus completing a circuit through the heating element 179 of a normally open delay tube 180, the circuit being from power terminal 150 through lines 132, 134, 136, 182, 184, 178, 160, 158 and 186 to power terminal 150'. Thus, after a predetermined time interval, the element 179 will heat sufficiently to close the tube 180, causing power to be applied to a second four way solenoid

valve 188 which controls the air cylinder 44. There is shown an air supply valve 190, a regulator 192, a pressure gage 194, a shut-off valve 196 leading to the solenoid valve 188, an exhaust line 198 for cylinder 44, a regulator 200, pressure gage 202 and shut-off valve 196' in a line 204 leading to the solenoid valve 142, and an exhaust line 206 for the air cylinder 12.

It will be understood that the valve 188 is normally positioned so as to maintain the piston rod 48 and rack 46 in their retracted or left-hand positions as viewed in FIGURES 1 and 2, and when the delay tube 180 closes so as to apply power to the valve 188, air is admitted to the cylinder 44 so as to push the rack 46 to the right until the end thereof engages the end of the adjustable stop screw 52. In this manner, the lower anvil 42 and lower anvil plate 114 are rotated through a predetermined angle, while the upper anvil 16 remains pressed against the lower anvil plate. In the particular example being described, the delay tube 180 is not adjustable, but of course a delay tube is selected having a desired predetermined time delay, such time delay being the time interval between the closing of the microswitch 172 by the descending anvil 16 and the actuation of the valve 188 to initiate rotation of the lower anvil plate 114. One example of a suitable tube 180 is a two-second delay tube. It takes approximately one-half second for the upper anvil 16 to engage the lower anvil plate 114 after tripping the microswitch 172, and thus in the example described there would be a delay of approximately one and one-half seconds between the time the upper anvil 16 engages against the lower anvil plate 114 and the time that rotation of the lower anvil plate is initiated.

As previously described, the time interval between the closing of the microswitch 172 and the retraction or raising of the upper anvil 16 is determined by the time delay relay 152a which can be set for any desired interval between 0 and 60 seconds. In the example being described, the relay 152a would be set for a time in excess of two seconds so as to assure that rotation of the lower anvil plate 114 is completed before the upper anvil 16 is raised. When the time delay relay 152a runs out, power is removed from the solenoid valve 142 and air is admitted to the cylinder 12 to raise the upper anvil 16, the anvil being suddenly snapped upwardly by the inrush of air. As the anvil 16 moves upwardly, the microswitch 172 is opened so as to remove power from the solenoid valve 188. Consequently, the valve 188 returns to its normal position thereby returning the rack 46 to its retracted position so as to cause the lower anvil 42 and anvil plate 114 to be rotated back to their original positions.

As described earlier herein, a test is conducted by attaching a test sample of coated paper to the blanket material 116 at the bottom of the upper anvil 16, and a piece of dark material such as black plastic electrician's tape is attached to the top of the lower anvil plate 114, a drop of aqueous solution such as lithographic fountain solution being placed on the black tape. During a test, the upper anvil 16 moves down into engagement with the lower anvil plate 114 pressing the test sample against the black tape and spreading the moisture over the contact area while squeezing out any excess moisture. Thereafter, the lower anvil plate 114 is rotated through a predetermined angle, e.g., up to two complete revolutions, so as to produce rubbing or frictional forces between the test sample and the black tape. A predetermined time after completion of the rotation of the lower anvil plate 114, the upper anvil 16 is suddenly moved upwardly away from the lower anvil plate thereby separating the test sample from the black tape and producing pick forces therebetween, such pick forces being dependent upon the speed at which the upper anvil is retracted. After retraction of the upper anvil 16, the lower anvil plate 114 is rotated back to its original position.

It will be understood from the foregoing that rub-

bing or frictional forces are first created between the test sample and the piece of black tape, and thereafter the pick forces are produced, the sequence being the same as actually occurs in a printing operation. Moreover, it is possible through adjustment of the time delay relay 152a to control the time interval between the application of the rubbing forces and the application of the pick forces so as to approximate the time interval which actually occurs in a printing operation where the rubbing forces are applied as the paper web moves through a nip defined between a pair of blanket rolls and the pick forces are applied as the paper web leaves the nip and is separated or peeled from the blanket surfaces. Thus, in accordance with the method and apparatus of the present invention, the test sample is subjected to both frictional or rubbing forces and pick forces in a timed sequence closely duplicating conditions which actually exist in a printing operation. As a result, the test provides an extremely accurate indication of the piling propensity of the paper being tested, even where the paper is of a type which exhibits a high degree of resistance to piling produced by pick forces and a low resistance to piling produced by rubbing forces, or vice versa.

The foregoing description explains the manner of controlling the time intervals between the various operations in a test as well as the manner of controlling the degree of rotation of the lower anvil plate 114. In addition, it should be noted that by adjusting the valve 196 in the air circuit for the cylinder 44, it is possible to control the speed of rotation of the anvil plate 114. In a similar manner, by adjusting the valve 196' in the air circuit to the cylinder 12, it is possible to control the lift-off speed, i.e., the speed at which the upper anvil 16 moves upwardly away from the lower anvil plate 114. The latter speed determines the severity of the pick forces which are produced, and in certain situations if desired the lift-off speed may be set very low so that the pick forces are negligible, in which case the resultant test is essentially a wet rub test. It will further be noted that in special situations the valve 196 in the air circuit to the cylinder 44 may be closed, in which case the lower anvil plate 114 will not rotate and the result will be a wet pick test without rubbing forces. Accordingly, the apparatus of the present invention can be used to provide only a wet pick test or only a wet rub test, although the essential objective is to provide a combination pick-rub test.

Upon carrying out a pick-rub test in the manner described above, a certain amount of the coating material on the test sample will be deposited on the piece of black plastic tape against which the test sample was engaged. The coating material is more or less white in color and thus is readily visible on the black tape. Consequently, the piling propensity of the test sample can be determined by visually or optically comparing the black tapes to standards for numerical or similar grading, and the tape itself may then be attached to a record or report since the coating deposits on the tapes will readily adhere thereto so as to form a permanent visual record. One advantageous technique is to use a brightness meter for measuring the reflectance of the black tapes, and various known types of instruments can be used for this purpose, it being understood that the more coating there is on the tape the greater will be the reflectance reading. Another technique is to provide a previously prepared set of calibrated samples so that the test specimen tape may be compared with the set of samples to obtain a rating as to piling propensity.

The apparatus described herein is also adapted for penetration testing of paper test specimens. In order to conduct a penetration test, the function switch arm 120 is positioned to engage the upper terminal 122, thereby bringing into the circuit an interval timer 208, and the air valve 196 is closed so as to prevent rotation of the lower anvil plate 114. For purposes of a penetration test, the piece of blanket material 116 is removed from the

upper anvil 16, a test sample is secured directly to the bottom of the upper anvil, and a drop of moisture is placed on the top of the lower anvil plate 114. The push button 130 is depressed causing the upper anvil 16 to move downwardly against the lower anvil plate 114 in the manner previously described due to the holding circuit established to the solenoid valve 142 through the normally closed contacts 152b and 154b and the normally open contact 148b. As the moisture begins to penetrate the test sample, a current flow is established, the circuit being from one side of a battery 210 through line 212 to the lower anvil plate 114, through the test specimen to the upper anvil 16, lines 158 and 214, and through voltage sensitive relay 154a and milliammeter 216 to the opposite side of the battery 210.

It will further be noted that as the descending upper anvil 16 closes the microswitch 172 in the manner previously described, power is applied to the interval timer 208 to initiate the beginning of a measured time cycle. As the test sample deteriorates and moisture penetration therethrough increases, the current flow through the sample and through the voltage sensitive relay 154a increases until a predetermined magnitude of current flow pulls in the relay 154a and opens the normally closed contact 154b, thereby removing power from the solenoid valve 142 and causing retraction of the upper anvil 16. As the anvil 16 retracts upwardly, it opens the microswitch 172 breaking the circuit through the interval timer 208 so as to stop the latter. Accordingly, the reading on the timer 208 indicates the time required to develop a predetermined amount of penetration of the test sample. The interval timer 208 measures the time from the closing of microswitch 172 to the opening thereof, and such interval is dependent upon the time required to develop an amount of penetration through the test sample so as to produce a predetermined current flow therethrough sufficient to pull in the voltage sensitive relay 154a.

While we have described our invention in certain preferred forms, we do not intend to be limited to such forms, except insofar as the appended claims are so limited, since modification coming within the scope of our invention will readily occur to those skilled in the art, particularly with our disclosure before them.

We claim:

1. Apparatus for determining the piling propensity of paper or the like comprising, in combination, first and second anvil means positioned in axial alignment and in opposed facing relation to one another, one of said anvil means having a test specimen secured to the end thereof during a test cycle, one of said anvil means also being movable axially toward and away from the other anvil means and one of said anvil means being rotatable about its longitudinal axis relative to the other anvil means, first actuating means for moving the axially movable one of said anvil means toward the other anvil means and into engagement therewith under pressure, and second actuating means operable during such engagement for rotating the rotatable one of said anvil means through a predetermined angle relative to the other anvil means, said first actuating means being operable subsequent to said rotation to effect sudden separation of said first and second anvil means.

2. The invention of claim 1 where said first anvil means is movable toward and away from said second anvil means, and where said second anvil means is rotatable about its longitudinal axis relative to said first anvil means.

3. The invention of claim 1 including adjustable stop means for controlling the angle through which the rotatable anvil means is rotated during a test cycle.

4. The invention of claim 1 including first timing means associated with said first actuating means for controlling the time of engagement between said first and second anvil means, and second timing means associated with

said second actuating means for initiating rotation of the rotatable anvil means a predetermined time after initiation of said engagement and before termination of said engagement.

5. The invention of claim 4 where said first timing means is adjustable in order to adjust the duration of said engagement and thereby adjust the time interval between the rotation of the rotatable anvil means and the separation of said first and second anvil means.

10 6. The invention of claim 1 where said first and second actuating means comprise first and second double-acting air cylinders, and where said second actuating means further includes gear means for rotating the rotatable anvil means and rack means actuated by said second double-acting air cylinder and in mesh with said gear means for driving the latter.

15 7. The invention of claim 6 including an adjustable stop positioned for engagement by said rack means so as to limit the linear stroke thereof, said stop thereby serving to control the angle of rotation of the rotatable anvil means during a test cycle.

20 8. The invention of claim 6 including first adjustable valve means located in an air circuit to said first double-acting air cylinder for controlling the speed at which one 25 of said anvil means is moved toward and away from the other of said anvil means, and second adjustable valve means located in an air circuit to said second double-acting air cylinder for controlling the speed at which the rotatable anvil means is rotated by said rack means.

30 9. Apparatus for determining the piling propensity of paper or the like comprising, in combination, lower anvil means mounted for rotation about a vertical axis and having a substantially flat horizontal top surface, upper anvil means disposed above said lower anvil means in axial alignment therewith and having a substantially flat 35 horizontal bottom surface in opposed facing relation to said top surface, one of said surfaces having a test specimen secured thereto during a test cycle, said upper anvil means being movable downwardly and upwardly toward and away from said lower anvil means, first air cylinder means for rotating said lower anvil means through a predetermined angle, second air cylinder means for moving said upper anvil means downwardly into engagement under pressure with said lower anvil means and subsequently 40 upwardly away from said lower anvil means, and first and second timing means associated with said first and second air cylinder means respectively, said second timing means serving to control the time of engagement between said upper and lower anvil means, and said first timing means serving to initiate rotation of said lower anvil means a predetermined time after initiation of said engagement and before termination of said engagement.

45 10. The invention of claim 9 including rack and gear means actuated by said first air cylinder means for rotating said lower anvil means, and adjustable stop means for controlling the stroke of said rack means in order to control the angle of rotation of said lower anvil means.

50 11. The invention of claim 9 where said second timing means is adjustable in order to adjust the duration of said engagement and thereby adjust the time interval between the rotation of said lower anvil means and the upward retraction of said upper anvil means.

55 12. A method of determining the piling propensity of coated paper or the like comprising the steps of pressing a test specimen of the paper into engagement with a flat piece of dark-colored material which is wetted with a small amount of aqueous solution, maintaining a predetermined force on said specimen to hold the same under pressure against said dark-colored material for a predetermined time, rotating said specimen and said dark-colored material through a predetermined angle relative to one another about an axis perpendicular to the plane of said specimen, suddenly separating said specimen and said dark-colored material subsequent to the completion

of said rotation, and measuring the amount of coating transferred from said specimen to said dark-colored material.

13. A method according to claim 12 where the separation of said specimen and said dark-colored material is carried out a selected predetermined time after said relative rotation of said specimen and said dark-colored material.
